UNITED STATES PATENT OFFICE.

ELIHU THOMSON, OF SWAMPSOFT, MASSACHUSETTS, ASSIGNOR TO GENERAL ELECTRIC COMPANY, A CORPORATION OF NEW YORK.

CONDENSING APPARATUS.

1,080,734.

Specification of Letters Patent. Patented Dec. 9, 1913.

Application filed March 2, 1908. Serial No. 418,763.

To all whom it may concern:

Be it known that I, ELIHU THOMSON, a citizen of the United States, residing at Swampscott, in the county of Essex, State of Massachusetts, have invented certain new and useful Improvements in Condensing Apparatus, of which the following is a specification.

The present invention relates to condensing systems for steam turbines or other prime movers and has for its object to improve and simplify their construction and mode of operation.

In carrying out my invention, a turbine or other prime mover is provided, which receives steam from a suitable boiler and exhausts into a surface condenser. This condenser may be cooled by salt water or that from any suitable source, and the water need not be particularly clean since it does not mix with the water of condensation. The reciprocating air pump such as is commonly used to extract air from the condenser system, forms, in most installations, a large portion of the plant. I dispense with such a pump and substitute therefor a barometric column of about thirty-four or thirty-five feet in height. The upper end of the column is usually provided with a nozzle having a throat which has an anterior converging portion and a posterior diverging portion. The anterior portion is further enlarged to form a chamber, and connecting this chamber with the exhaust steam space of the condenser is a conduit through which air and a small amount of uncondensed vapor are drawn by the action of the water of condensation flowing through the barometric column. The lower end of this column enters a trap having means to control the discharge of air, such as an automatic pressure actuated valve or an air suction pump, and means to control the discharge of water, such as an automatic float actuated water valve. The air subsequent to entering the trap with the water separates therefrom and enters a chamber at the top from which it escapes from time to time when the pressure is great enough to open the self-closing valve. When the water level reaches a certain height it opens the float valve and permits water to escape from the trap. The water necessary to operate the barometric column is taken from the hot well of the condenser and raised by a high-speed cen-

trifugal pump. Under some conditions it may be impossible or undesirable to have a long vertical column owing to the lack of head room or for some other reason. In such cases I may make the column shorter and connect a suitable air pump to the air chamber in the trap at the lower end of the fall column. Owing to the fact that the air by the time it reaches the trap and is liberated from the water is much more dense than that in the condenser itself, no trouble will be experienced in pumping it out with a comparatively small and simple high speed pump.

In order that the water of condensation may work to the best advantage in the column, a cooling means is employed therefor which means may with advantage, be acted upon by the circulating water before it enters the condenser. A centrifugal pump draws water of condensation through the cooling means, and discharges it through a nozzle located in the chamber in the top of the column. As the water descends it withdraws air from the condenser and usually a small amount of uncondensed vapor. The pump should be either located below the level of the hot well and cooling means or else arrangements must be made for priming it with a check valve to prevent back flow from the pump toward the cooling means. The pump may be driven by a turbine, or an electric motor and the latter may with advantage receive its energy from the generator driven by the main prime mover.

Since it is necessary to supply the boiler with water, I utilize the same pump for this purpose that supplies the barometric column. In the case of the column the pressure necessary to raise the water is comparatively small while that necessary to force water into the boiler must necessarily be considerably greater. To carry out this part of my invention, I provide a centrifugal pump comprising a suitable casing with inlets and outlets and an impeller having portions of different diameter, that having the smaller diameter being used to supply water to the column and that having the larger diameter being used to supply the boiler. It will thus be seen that the water of condensation is kept entirely separate from the cooling or circulating water, and that it is returned to the boiler to maintain its level and is supplied to the column to extract air from the

condenser. In such a system it will be found necessary to add a certain amount of make-up water from time to time on account of leakage, and this may be done in the usual manner.

In the accompanying drawing which illustrates one of the ways of carrying out my invention, Figure 1 shows diagrammatically a condensing system receiving the exhaust 10 from a steam turbine; Fig. 2 is an axial section of the centrifugal pump taken on line 2-2 of Fig. 1, and Fig. 3 is a cross section showing the lower end of the barometric column and taken on the line 3-3 of Fig. 1. 15 1 indicates a steam turbine or other prime mover which is directly connected to the electric generator 2. Steam for the prime mover is supplied by the boiler 3, and the exhaust of the turbine is conveyed by the 20 conduit 4 to the surface condenser 5. The latter may be of any suitable construction. In the present instance, it comprises tube sheets 6 located at opposite ends for supporting the tubes 7. These tubes are in communication with chambers 8 in opposite ends which are filled with cooling or circulating water. This water is supplied by the 25 conduit 9 and is discharged by the conduit 10. The former is connected with a suitable 30 water supply in any convenient manner.

In order to extract the air from the vapor space of the condenser a Torricellian or barometric column 11 is provided. This column is thirty-four or thirty-five feet high and at 35 the upper end is provided with a nozzle 12 which first converges and then diverges. The water of condensation from the hot well is discharged into the downwardly opening nozzle 13. Surrounding the discharge nozzle 13 is a chamber 14 which is connected by the conduit 15 with the vapor space of the condenser. As the water descends through the column 11 it carries with it the air and some uncondensed vapor from the 40 condenser.

The lower end of the column extends into a trap 16 provided with a suitable casing having a chamber 17 for air and a chamber 18 for water, the two being in constant 45 communication through orifices 19. The lower end of the column is provided with a cross piece 20 of the shape shown in Fig. 3. The object of this is to impart to the water issuing from the column a rotary motion, 50 which will permit the air to separate from the water at a point or points near the column and pass into the chamber 17. When the pressure accumulates to a certain point it will open the valve 21 and be discharged, 55 after which the small weight 22 or other means closes the valve. Inside of the water chamber 18 is a valve 24 that controls the outlet to the pipe 25 and is actuated by the float 26. When the water within the cham-

ber rises to a predetermined level, it opens 65 the valve and permits water to escape until the level has decreased to a certain amount when the valve automatically closes. The pipe 25 is in direct communication with the hot well 27 of the condenser, and the latter 70 is connected with the suction side of the centrifugal pump 28. Included in the connection between the hot well and the pump is a cooling means 29 which may be made in a variety of ways. In the present instance it 75 is shown as being composed of a coil of pipe bent back and forth on itself. This coil is inclosed in a casing 30 which forms a part of the conduit conveying cooling water to the condenser. The water from the hot well 80 is elevated by the centrifugal pump and after passing through the conduit 31 is discharged by the nozzle 13. The same pump also conveys water by the pipe 32 to the boiler 3. This pump is driven by a motor, 85 such as a steam turbine or an electric motor located on the side away from the observer. The construction of the pump is best shown in Fig. 2, wherein 33 indicates the driving shaft and 34 the impeller mounted thereon. 90 This impeller comprises two portions, 35 and 36, which differ in diameter. The portion 35 having the smaller diameter will impart less pressure to the water than the portion 95 having the larger diameter, and for this reason the former is employed to supply water to the barometric column, and the latter to supply water to the boiler. The impeller is located in a suitable casing having supply chambers 37 on opposite sides thereof, and 100 low pressure outlets 38 and a high pressure outlet 39. It is to be noted that the cooling water piping or system has no connection with that of the water of condensation, the two being entirely distinct, and that the 105 water of condensation is employed for extracting air from the condenser.

When the column 11 has to be made shorter for one reason or another a suction air pump 40 is provided, which is driven by 110 an electric motor, or other suitable agency, and is connected on the suction side to the air chamber 17 at the lower end of the fall column 11. As the density of the air in this chamber is relatively high the labor of 115 pumping will be comparatively light, and the pump need only be of a comparatively small size.

By reason of my invention, I have avoided all the complications made necessary by 120 the use of reciprocating pumps, and substituted therefor apparatus that occupies a minimum amount of room, and which is very simple and of a relatively cheap construction.

For the barometric column spoken of, may be substituted a jet impelled by sufficient force to carry the air forward with it and

deliver the same through the water seal into the chamber from which it afterward escapes. Such a jet arrangement I would consider a substitute for that part of my invention comprising the barometric column, since the force of the water jet supplies the necessary difference of pressure instead of the height of the column.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States, is—

1. In combination, a prime mover, a surface condenser that receives all of the exhaust vapor from the prime mover and condenses it, means for supplying cooling water to the condenser and maintaining it separate from the water of condensation, a means separate from the condenser and connected to its vapor space that acts solely to extract air and uncondensed gases from the condenser and comprises a fall column, and a pump which receives water of condensation only from the condenser and discharges it into the upper end of said column, the cooling water and the water of condensation being separately maintained.

2. In combination, a prime mover, a surface condenser that receives all of the exhaust vapor from the prime mover and condenses it, means for supplying cooling water to the condenser and maintaining it separate from the water of condensation, a means which acts solely to extract air and uncondensed gases from the condenser that comprises a fall column, a connection from the top thereof to the vapor space at the top of the said condenser, a centrifugal pump that receives water of condensation only from the condenser and discharges it into the upper end of said column, and an air trap located at the bottom of the column in which the water and vapors separate.

3. In combination, a prime mover, a surface condenser that receives all of the exhaust vapor from the prime mover and condenses it, means for supplying cooling water to the condenser and maintaining it separate from the water of condensation, a means which acts solely to extract air and uncondensed gases from the condenser that comprises a fall column, a connection from the top of the column to the vapor space at the top of said condenser, and an automatically acting trap with which the lower end of the column communicates, which trap discharges air when the pressure therein

reaches a certain predetermined value and 65 discharges the water of condensation when the level thereof exceeds a certain predetermined point.

4. In combination, a prime mover, a surface condenser that receives all of the exhaust vapor from the prime mover and condenses it, means for supplying cooling water to the condenser and maintaining it separate from the water of condensation, a means which acts solely to extract air and 70 uncondensed gases from the condenser that comprises a fall column, a connection between the upper end of the column and the vapor space of said condenser, an automatic trap into which the lower end of the column 75 extends, said trap being constructed and arranged to release the air contained therein when the pressure exceeds a predetermined value and to discharge water of condensation when the level thereof exceeds a certain 80 point, a cooler for the water of condensation, a connection between the trap and the lower part of the condenser and the cooler, and a centrifugal pump which receives water of condensation unmixed with the cooling water from the cooler and discharges it 85 into the upper end of the column.

5. In combination, a prime mover, a boiler for supplying vapor thereto, a surface condenser that receives all of the vapor exhausted from the prime mover and condenses it, means for supplying cooling water to the condenser, said cooling water being maintained entirely separate from the water of condensation, a means separate 95 from the condenser that acts solely to extract air from the condenser and comprises a fall column, a connection between the vapor space at the upper part of the condenser and the top of the column, and a trap 100 connected to and receiving the water of condensation from the column, said trap acting to control the escape of air from the water, and a centrifugal pump connected to and receiving water from the lower part of 105 the condenser and from the trap after air has been separated therefrom which pump discharges water of condensation at different pressures to the upper end of the column and to the boiler respectively.

6. In combination, a prime mover, a boiler for supplying vapor thereto, a surface condenser that receives all of the vapor exhausted from the prime mover and condenses it, means for supplying cooling water to the condenser, said cooling water being maintained entirely separate from the water of condensation, a means separate from the condenser that acts solely to extract air from the condenser and comprises 115 a fall column, a connection between the vapor space of the condenser and the top of the column, and a trap connected to and re-

- ceiving the water of condensation from the column, said trap acting to control the escape of air from the water, and a centrifugal pump connected to and receiving water of condensation from the trap after air has been separated therefrom which discharges said water to the upper end of the column at one pressure and to the boiler at a different pressure, a cooler through which the water of condensation passes before entering the pump, and means for conveying the cooling water over the surfaces of the cooler on its way to the condenser.
7. In combination, a boiler, a prime mover supplied with vapor therefrom, a condenser that receives all of the exhaust vapor from the prime mover, means for circulating a cooling liquid through the condenser and keeping it out of contact with the liquid caused by condensation of the exhaust vapor, a fall column, a connection between the column and the upper end of the condenser to remove air from said condenser, an automatically acting trap at the bottom of the column, a centrifugal pump that is located below the level of the condenser and receives liquid due to condensation therefrom un-

mixed with the cooling water and from the trap and supplies it to the column, and a means for reducing the temperature of the liquid prior to its discharge into the upper end of the column.

8. In combination, a prime mover, a surface condenser for condensing all the exhaust vapor therefrom, conduits delivering circulating water to and receiving it from the condenser, a fall column, a connection from its upper end to the vapor space of the condenser, a pump which receives the water of condensation unmixed with the circulating water from the condenser and discharges it into the top of column where by its fall it creates a suction in said connection thereby extracting air from the condenser, and means coöperating with the lower end of the column to control the discharge of air and the water of condensation.

In witness whereof, I have hereunto set my hand this twenty sixth day of February, 1908.

ELIHU THOMSON.
